SAILBOAT

Joseph Lyman, Huntington, N. Y., assignor to Aero-Nautical Boat Shop, Inc., Halesite, N. Y., a corporation of New York

Application October 26, 1954, Serial No. 32,825

Term of patent 14 years

(Cl. D71—1)

Fig. 2.

Fig. 3.

Fig. 4.

Fig. 5. Fig. 6. Fig. 7. Fig. 8. Fig. 9.

Fig. 1 is a perspective view of a sailboat showing my new design;

Fig. 2 is a side elevational view thereof;

Fig. 3 is a rear elevational view thereof;

Fig. 4 is a top plan view of the hull shown in Figs. 1, 2 and 3; and

Figs. 5 through 9 are sectional views taken on lines 5—5 through 9—9, respectively, of Fig. 4.

I claim:

The ornamental design for a sailboat, as shown.
